UNITED STATES PATENT OFFICE.

PARKER JENKINS, OF PHILADELPHIA, PENNSYLVANIA.

DIMMER-SHIELD FOR LAMPS.

1,346,497.

Specification of Letters Patent. Patented July 13, 1920.

Application filed August 31, 1917. Serial No. 187,886.

To all whom it may concern:

Be it known that I, PARKER JENKINS, a citizen of the United States, residing at Philadelphia, in the county of Philadelphia and State of Pennsylvania, have invented new and useful Improvements in Dimmer-Shields for Lamps, of which the following is a specification.

My invention relates to new and useful improvements in dimmer shields for lamps and has for its object to provide an exceedingly simple and effective device of this character, whereby the rays of light issuing from a lamp will be prevented from striking the eyes of pedestrians, drivers of other vehicles or beasts of burden traveling along the roadway which is being traversed by the vehicle carrying lamps equipped with my improvement.

20 A further object of the invention is to provide a new and improved construction for fastening shields of this character to the lamp rim.

With these ends in view, this invention 25 consists in the details of construction and combination of elements hereinafter set forth and then specifically designated by the claims.

In order that those skilled in the art to 30 which this invention appertains may understand how to make and use the same, I will describe its construction in detail referring by numerals to the accompanying drawings forming a part of this application in 35 which—

Figure 1, is a side elevation of a lamp showing my improved dimmer shield applied thereto.

Fig. 2, is a front elevation thereof, and 40 Fig. 3, is an enlarged fragmentary view of the lamp embodying my improvement, portions thereof being broken away, and shown in section to clearly illustrate the construction.

45 In carrying out my invention as here embodied, 2 represents a lamp of any desirable construction and configuration, provided with a rim 3 adapted to carry the front glass or lens 4 which may be attached to the lamp 50 in any desirable and well known manner.

In the front wall of this rim 3 is cut an

arcuate slot, and at each end of said slot is cut a short slot projecting from the arcuate slot at an angle thereto so as to partially separate a part of the material of the 55 rim, which material is then bent at an angle to the face of the rim to produce a flange 5. The material thus partly cut from the rim is preferably bent outward so as to form the outwardly projecting flange as shown leaving an arcuate opening 6.

The reference numeral 7 denotes the dimmer shield in the form of a quarter sphere and the inner edge which is approximately the same length as the arcuate flange 5 underlies said flange and projects into the opening 6, said shield being attached to the flange in any suitable and well known manner as by welding, soldering, or by some suitable attaching means, such as rivets 8 as here 70 shown.

Although I have shown the dimmer shield underlying the flange 5, it will be obvious that approximately the same result will be obtained if the shield is placed over the 75 flange and fastened thereto.

As here shown, the dimmer shield is disposed across approximately one-half of the front glass or lens of the lamp so that the rays projecting from the upper portion 80 thereof will be deflected toward the roadway so that the glare from the lamp will not shine in the eyes of persons looking toward said lamp, thus reducing to a minimum the likelihood of loss of life or property which 85 is often occasioned because of the confusion produced by the glare from high power lamps.

Of course I do not wish to be limited to the exact details of construction as herein 90 shown as these may be varied within the limits of the appended claims without departing from the spirit of my invention.

Having thus fully described my invention what I claim as new and patentable is— 95

1. In a device of the character stated a lamp rim having an arcuate section of its metal partially cut therefrom and bent to produce a flange and a dimmer shield having one edge thereof attached to said flange. 100
2. In combination, a lamp provided with a rim adapted to carry the front glass, said

rim having an arcuate section of its front wall partially cut therefrom and bent outward to provide a flange thereby leaving an opening, a dimmer shield in the form of a 5 quarter sphere having its inner edge underlying the flange and projecting into the opening, said shield being disposed across ap-

proximately one-half of the front glass of the lamp and means for fastening said dimmer shield to the flange.

10

In testimony whereof I have hereunto affixed my signature.

PARKER JENKINS.
